(57) **CLAIM**

The ornamental design for a battery charger, as shown and described.

DESCRIPTION

FIG. 1 is a front perspective view of a battery charger showing my design.

FIG. 2 is a top plan view thereof.

FIG. 3 is a right side elevational view thereof. The left side is a mirror image of the right side.

FIG. 4 is a rear elevational view thereof.

FIG. 5 is a front elevational view thereof; and, FIG. 6 is a bottom plan view thereof.
